UNITED STATES PATENT OFFICE.

ANELITE P. THOMPSON, OF SAN DIEGO, CALIFORNIA.

DESIGN FOR A DRESS.

Application filed August 6, 1923. Serial No. 6,961. Term of patent 3½ years.

To all whom it may concern:

Be it known that I, ANELITE P. THOMPSON, a citizen of the United States, residing at San Diego, in the county of San Diego and State of California, have invented a new, original, and ornamental Design for a Dress, of which the following is a specification, reference being had to the accompanying drawing, forming part thereof.

Figures 1 and 2 are elevations partly in perspective of the opposite sides of the dress, either of which may be considered as a front elevation, as the article is reversible.

I claim:

The ornamental design for a dress, as shown.

ANELITE P. THOMPSON.
